(57) CLAIM

We claim the ornamental design for a smoking article pack, as shown and described.

DESCRIPTION

FIG. 1 is a front top right perspective view of the smoking article pack showing the design of a first embodiment of the disclosed invention;

FIG. 2 is a front view thereof;

FIG. 3 is a rear view thereof;

FIG. 4 is a right side view thereof;

FIG. 5 is a left side view thereof;

FIG. 6 is a bottom view thereof;

FIG. 7 is a top view thereof;

FIG. 8 is a front top right perspective view of a second embodiment of smoking article pack;

FIG. 9 is a front view thereof;

FIG. 10 is a rear view thereof;

FIG. 11 is a right side view thereof;

FIG. 12 is a left side view thereof;

FIG. 13 is a bottom view thereof; and,

FIG. 14 is a top view thereof.
